[57] CLAIM

The ornamental design for a tripod, as shown and described.

DESCRIPTION

FIG. 1 is a top, front perspective view of a tripod, in a collapsed position showing my new design;

FIG. 2 is a top plan view thereof, at an enlarged scale;

FIG. 3 is a bottom plan view thereof;

FIG. 4 is a left side elevational view thereof, at a reduced scale;

FIG. 5 is a right side elevational view thereof;

FIG. 6 is a top, front perspective view thereof, in an expanded position;

FIG. 7 is a top plan view thereof;

FIG. 8 is a bottom plan view thereof;

FIG. 9 is an enlarged fragmentary view of a top, front of the tripod in a partially expanded position; and,

FIG. 10 is a fragmentary view of a bottom perspective view thereof, in a collapsed position.
